(57) **CLAIM**

The ornamental design for a storage container for electrical components, as shown and described.

DESCRIPTION

U.S. patent application Ser. No. 13/117,342, which is filed concurrently herewith, discloses related subject matter and is hereby incorporated by reference in its entirety.

FIG. 1 is a front perspective view of a cap of a storage container in accordance with an exemplary embodiment of the present invention;

FIG. 2 is a top plan view of the cap of FIG. 1;

FIG. 3 is a side elevational view of the cap of FIG. 1;

FIG. 4 is a front elevational view of the cap of FIG. 1;

FIG. 5 is a bottom plan view of the cap of FIG. 1;

FIG. 6 is a side elevational view in cross section of the cap of FIG. 1;

FIG. 7 is a perspective view of a jar of a storage container in accordance with an exemplary embodiment of the present invention;

FIG. 8 is a top plan view of the jar of FIG. 7;

FIG. 9 is a side elevational view of the jar of FIG. 7;

FIG. 10 is a front elevational view of the jar of FIG. 7;

FIG. 11 is a bottom plan view of the jar of FIG. 7;

FIG. 12 is a side elevational view in cross section of the jar of FIG. 7;

FIG. 13 is a perspective view of the cap of FIG. 1 connected to the jar of FIG. 7 to form a storage container in accordance with an exemplary embodiment of the present invention;

FIG. 14 is a top plan view of the storage container of FIG. 13;

FIG. 15 is a side elevational view of the storage container of FIG. 13;

FIG. 16 is a front elevational view of the storage container of FIG. 13;

FIG. 17 is a bottom plan view of the storage container of FIG. 13;

FIG. 18 is a side elevational view in cross section of the storage container of FIG. 13; and,

FIG. 19 is a front perspective view of a cap in accordance with another exemplary embodiment of the present invention having an upper portion with a concave inner surface. All other features of the cap are substantially identical to the cap of FIGS. 1-6.
